PRINTING ADDING MACHINE

Hugo Kämmel, Zella-Mehlis II, Germany, assignor to Mercedes Buromaschinen-Werke Aktiengesellschaft, Benshausen, Germany

Application June 28, 1932, Serial No. 619,769
In Germany March 14, 1931

2 Claims. (Cl. 235—59)

The invention relates to a printing adding machine, with column counters arranged on the paper carriage.

Printing adding machines have been provided with column counters, which are arranged on the paper carriage, in order that these machines can execute column work as this can be performed in typewriting calculating machines. The advantage of typing text however, is lost in such machines. The typing of text is particularly indispensable in pay and invoice matters.

This disadvantage is obviated according to the invention in which the printing adding machine is combined with a typewriting machine, both machines being advantageously arranged side by side.

According to a preferred form, both machines are provided with a common paper carriage, which carries the column counters.

20 In the drawings one example of the invention is represented.

Figure 1 shows (on a reduced scale) a front elevation of a power-driven typewriting machine coupled with an adding machine.

25 Figure 2 shows a plan of Fig. 1, likewise on a reduced scale.

Fig. 3 shows on an enlarged scale a side elevation of Fig. 1, viewed in the direction of the arrow A in Fig. 1, in which the casing of the machine is omitted and various parts are shown in section in order to render visible the cross totalizers and the mechanisms actuating them.

Fig. 3a shows diagrammatically the mutual displacability of the cross totalizers.

35 Fig. 4 shows a part elevation, on an enlarged scale, of Fig. 3, the mechanisms being in their position of rest.

Fig. 5 shows a further enlarged part elevation of Fig. 3, in which the mechanisms are represented in the position of rest.

40 Fig. 6 shows a cross totalizer in which the position shown in full lines represents the normal position and the position shown in dotted lines represents the position for addition.

45 Fig. 7 shows a cross totalizer according to Fig. 6, in which, however, the position shown in dotted lines represents the position for subtraction.

Fig. 8 shows on an enlarged scale a shift lock which co-acts with a stop carriage.

50 Fig. 8a is a section through the fixed dog according to line 8a—8a in Fig. 8 viewed in the direction of the arrows at said line. In Fig. 8a the fixed dog is shown in engagement with a tooth of the stop carriage rack, whereas the loose dog is omitted.

Fig. 9 shows an elevation of Fig. 8 viewed in the direction of the arrow B.

55 Fig. 10 shows in perspective the controlling mechanisms for the neutral, total and sub-total positions for the cross totalizer Q1.

Fig. 11 shows besides the mechanism for the cross totalizer Q1, also the controlling mechanism for the cross totalizer Q which mechanism is the same as the mechanism for the totalizer Q1. Fig. 11a shows a view of a detail of Fig. 11, seen in the direction of the arrow 129b in that figure. Fig. 12 is a perspective view of details of the print mechanism. Fig. 13 is a perspective view of some details of Figs. 2 and 3.

Fig. 14 shows diagrammatically a plan view on the totalizer Q in the direction of the arrow N as viewed in Fig. 5.

General description

The typewriting machine, 2, is arranged at the right hand, and the adding machine, 3, at the left hand of a common base plate 1 (Fig. 1).

The typewriting machine, 2, is provided with the usual letter typing keys, 4, and figure typing keys, 5, which letter and figure typing keys are connected in a known manner with the type levers, 6, (Fig. 2). Underneath and in front of the letter keys, 4, are arranged 10 calculating keys, 7, with the numbers 0 to 9 for the adding machine, 3. The levers, 8, of the calculating keys, 7, (Fig. 25 3) at their rear ends are mounted on bearings at, 9, so as to be capable of oscillation, and by means of a pin and slot connection, 10, 11, they are connected to setting levers, 14, for the stop carriage, 15, of the adding machine, 3. The levers project towards the left and are pivotably mounted in bearings on bearing blocks, 13, (of any suitable type) attached to the machine frame in any suitable manner. If a calculating key, 7, is depressed, the lever, 14, connected with the key lever, 8, is swung in the clockwise direction and by means of the upwardly projecting rear end, 16, of the same, the corresponding stop, 17, is set in the stop carriage, 15, and is held by means of a spring, 18, in this working position. The stop carriage, 15, as is evident in Figs. 2 and 3, is slidably arranged, by means of rollers, 19, on two rails, 20 and 21, fixed in the machine, and for the remainder is arranged similarly to the stop carriage represented and described in Patent Specification No. 1,329,028.

Against the stops, 17, set as above described the feeler rods, 23, (Fig. 3) are released on the operation of the machine by means of a crank handle (not shown) or through the depression 50 of a motor key, 22, (Figs. 1 and 2), whereby under the action of the springs, 25, acting on the type printing rods, 24, and through the pin and slot connections, 26, 27, and the sectors 29, carrying the toothed segments, 28, 28a and 28b, 55 and the pin and slot connection, 30, 31, the feeler projections, 32, of the feeler rods are carried against the set stops, 17, whereby the driving sectors, 29, and the toothed segments, 28, 28a and 28b, rotatably mounted on it, are rotated 56

in the clockwise direction corresponding to the set value and in their return movement introduce this value into the totalizers. By means of the slots, 23a and 23b, in the feeler rods, 23, into which project suitable screws, 23c and 23d, arranged in any suitable manner on the machine frame, the feeler rods are displaceable in the direction of the arrow *f*.

As soon as the type-printing rods 24 have been raised by their springs 25 in accordance with the amount set up by means of the calculating keys 1, the hammer mechanism—which will be described later on in a more detailed manner—is operated to thrust the types against the platen 33 which is common to the adding machine 3 as well as the typewriting machine 2.

Pin carriage escapement

In the operation of one of the calculating keys 1, the rearwardly directed part of the lever, 14, (Figs. 3 and 13) acts with its upwardly directed edge, 14a, on a yoke, 20x, swingably mounted at the points, 20a and 21a, on the running rails, 20 and 21. The yoke, 20x, at the part, 20c, connecting the limbs, 20b and 21b, is downwardly angled and is provided with teeth, 20d, between which the rearwardly directed levers, 14, which at their free ends are bent towards the left, (Fig. 2), are capable of projecting and in this way are simultaneously guided. The yoke, 20x, now, on the striking of one of the calculating keys, 1, can act in any suitable manner on the nose 20F of the part 20G of the shift lock 20A, (Figs. 3, 8, 9, and 13), for instance 30 through the intermediary of a lever 20b' fixed to the limb 20b of the yoke 20x, and effect a step movement of the stop carriage to the left (Fig. 2), which process will not be further described here, as this is generally known. In the following, 40 solely for the sake of completeness, the shift lock, 20A, will be described.

By means of the screws, 20B, (Figs. 3, 8 and 9) a plate, 20C, is secured to the machine frame, which is rearwardly bent at its free end, and 45 is provided with two lateral downwardly projecting U-shaped limbs, 20D. In threaded holes, not shown, provided in the limbs, 20D, screws, 20E, are inserted, around the points of which the part, 20G, carrying the fixed shift-tooth, 50 20F, is swingably mounted by means of its upwardly bent lugs, 20H. The spring, 20y, which at one of its ends is connected to the part, 20I, of the part, 20G, and at its other end is connected to the part, 20C, acts on the part, 20G, 55 in the anti-clockwise direction around the screws, 20E, (Fig. 9), whereby the part, 20G, presses upwards against the screw, 20K, of the part, 20C, and the normal position of the part, 20G, is thereby determined. The projection, 20L, of 60 the part, 20G, is constructed like a tooth, and this tooth, 20F, coacts with the teeth, 20M, (Fig. 8) of the rack, 20N, fixed to the stop carriage, 15. By means of the screw, 20P, a lever, 20Q, is swingably mounted on the part, 20G. 65 The pin, 20R, (Fig. 8) provided on the part, 20G, projects through an elongated hole, 20S, of the lever, 20Q. The spring, 20V, which is connected to the pin, 20T, of the part, 20G, and to the pin, 20u, of the lever, 20Q, acts on 70 the lever, 20Q, round its axis, 20P, in the anti-clockwise direction, so that the lever, 20Q, rests with its face, 20W, formed by one end of the elongated hole, 20S, against the pin, 20R, provided on the part, 20G, whereby the normal 75 position of the lever, 20Q, is determined. On

the lever, 20Q, a lug, 20Z, is upwardly bent, which lug co-acts with a lever to be later described.

At the point, 20g, a two-armed lever, 20h, is jointed to the part, 20Q, to a limb of which a spring, 20k, is attached, which, with its other end is connected to the lever, 20Q, and acts upon the two-armed lever, 20h, in the clockwise direction. The forwardly directed limb of this lever is provided with a projection, 20m, (Fig. 8), with which it can co-act with the projection, 20Z, 10 of the lever, 20Q. The rearwardly projecting tooth-like end, 20p, of the lever, 20h, is in engagement with the teeth, 20M, of the rack, 20N, of the stop carriage, 15, and as the stop carriage, 15, is acted upon in the direction of the 15 arrow, M, indicated in Fig. 8, by a spring, which is not represented, the lever, 20h, rests with its projection, 20r, against a lug, 20Qa, bent on the lever, 20Q, whereby the lever, 20Q, is again acted upon round the axis, 20P, in the anti-clockwise 20 direction and rests with the face, 20W, of its elongated hole, 20S, against the pin, 20R, whereby the normal position of the parts, 20Q, 20h, is determined.

The operation of the escapement is briefly as 25 follows:

On depression of a key 1, the rear end 16 (Figs. 3 and 13) of its key lever 14 sets a stop in the stop carriage 15. At the same time the yoke 20x (Fig. 13) is rocked upwards round its screws 30 20a and 21a. Thereby, the lever 20b', fixed to the yoke 20x raises the part 20G, which is rocked clockwise (viewed in Fig. 9) round the screws 20E against the action of the spring 20y. As a result, the loose dog 20p, 20h disengages the teeth 20M 35 of the rack 20N of the stop carriage whereas the oblique face of the fixed dog 20F engages the same as shown in Fig. 8a. Consequently, the loose dog 20p, 20h is rocked clockwise (Fig. 8) by means of its spring 20k, which movement is arrested by 40 the lug 20Z of the part 20Q. As a result, the tooth 20p of the loose dog is now just over the next tooth space of the rack 20N. As soon as the depressed key 1 is released, the spring 20y 45 (Fig. 9) restores the part 20G to its rest position. Thereby the fixed dog 20F releases the rack 20N and the tooth 20p of the loose dog enters the tooth space, lying opposite to it. By means of the stop carriage spring (not shown), the stop carriage is urged in the direction M (Fig. 8) until 50 the loose dog 20p, 20h impinges with its part 20r against the lug 20Qa. Thus the stop carriage is displaced one step in the direction of the arrow M (Fig. 8).

In the return of the stop carriage, 15, into its 55 initial position as represented in Fig. 2, the teeth, 20p, of the lever, 20h, slip over the teeth, 20M, of the rack, 20N, of the stop carriage, 15, whereby the lever, 20h, is swung round the point, 20g, in the clockwise direction, which takes place quite 60 freely, as in this swinging movement of the lever, 20h, the lever, 20Q, is also swung against the action of the spring, 20V, round the point, 20P, in consequence of the action of the projection, 20m, of the lever, 20h, on the lug, 20z, of the lever, 20Q. 65

Printing mechanism

The hammer mechanism and the mechanism actuating the same will next be described in detail.

The printing mechanism is arranged between the two printing mechanism frame walls arranged in the machine, of which in Fig. 4, however, only the right one is visible.

Between the two printing mechanism frame walls, 7

34, a part, 36, of angular formation having both of its free ends bent rearwardly at right angles is secured by means of the screws, 35, Fig. 4, to the right-hand printing mechanism frame wall, 34, 5 and is fastened by means of screws not shown to the left-hand printing mechanism frame wall, 34. This part, 36, is provided with as many slots, not shown, as there are printing rods 24.

The printing mechanism frame here illustrated 10 is arranged by way of example for ten denominational orders. The slots serve as guides for type printing rods, 24, to be later described in a more detailed manner. The type printing rods are so arranged that the distance between printed figures in adjacent orders is equal to the distance 15 of the letters of the typed text.

The angle-shaped part, 36, is still further provided with ten holes not shown, from which are hung the springs, 25, (Fig. 4), which at their 20 other ends are connected to the noses, 37, of the type printing rods, 24, and act upon these rods in the direction of the arrow, D.

By means of screws, 38, (Figs. 3 and 4) a part, 39, of angular formation and with its free ends 25 bent forwardly at right angles, is further fixed to the right printing mechanism frame wall, 34, and to the left printing mechanism frame wall, 34, by means of screws not shown. The part, 39, similarly to the part, 36, is provided with ten 30 slots not shown, which likewise serve as guides for the type printing rods, 24.

Further, in the zone of the lower ends of the type printing rods, 24, and between the two printing mechanism frame walls, 34, (Figs. 3 and 35 4) a part, 40, of U-shape having both its free ends bent upwards at right angles, is arranged. This is fastened to the right-hand printing mechanism frame wall, 34, by means of screws, 42, (Figs. 3 and 4) passing through its bent lug, 41, and to the left-hand printing mechanism frame wall, 34, which is not shown. The part, 40, is provided with ten slots, not shown, which serve as guides for the type printing rods, 24. The parts, 36, 39, 40 and 34, form the printing mechanism frame 45 proper.

On the upper ends of the type printing rods, 24, lugs, 43, (Fig. 4) are bent, so that a number of rectangular shaped recesses are formed, in which number types, 44, are slidably arranged. In Fig. 4, 50 the cover plate is omitted in order to render the number types, 44, visible. The number types, 44, which on their rearwardly directed ends, carry the types, 45, are provided with projections, 46 and 47, (Fig. 4). By means of compression springs, 48, 55 which on one side rest against the left-hand lugs, 43, of the type printing rods, 24, and on the other side rest against the faces of the projections, 46, of the number types, 44, the number types, 44, are held in their rest position, which is determined by 60 the contact of the right-hand faces, 46a, of the number types, 44, against the right-hand lugs, 43, of the type printing rods, 24.

On the noses, 49, of the type printing rods, 24, as already described, pins, 26, (Figs. 3 and 4) are 65 riveted, which are embraced by fork-shaped arms, 50, of the driving sectors, 29, swingable around the shaft, 51.

Differential mechanism

70 The driving sectors, 29, under the pull of the springs, 25, attached to the type printing rods, 24, rest with their parts, 52, against a bar, 53, (Fig. 4), which at its free ends is fixed to the angle lever, 54, (in Figs. 3 and 4 only the right hand 75 angle lever is visible). These two angle levers

which are arranged to the right and left of the driving sectors, 29, are swingably mounted on the shaft, 51. By means of springs, 55, which on the one side are connected to the angle levers, 54, and on the other side to pins, 55a, provided on the machine frame, the levers, 54, are acted upon in the clockwise direction. These and the bar, 53, also form a yoke. On each of the downwardly directed ends of the angle levers, 54, a roller, 56, is provided (in Fig. 4 only the right-hand roller is visible), each of which rests against a cam, 58, fixed on a shaft, 57, (in Figs. 3 and 4 only the right-hand cam is represented). By the action of the springs, 25, which on the one side are attached to the nose, 37, of the type printing rods, 24, and on the other side to the angle shaped part, 36, as already earlier mentioned, the type printing rods, 24, are acted upon in the direction of the arrow, D, and likewise the parts, 50 and 29. By the contact of the parts, 52, of the driving sectors, 29, with the bar, 53, and the contact of the roller, 56, of the angle lever, 54, with the cam, 58, the normal position of the parts, 24, 50, 29, 53, and 23, is determined.

The driving sectors, 29, (Figs. 3 and 4) are provided with lugs, 59, which co-act with projections, 60, of the three tooth segments, 28, 28a, and 28b, which are swingably mounted at the points, 61, on the driving sectors, 29. By means of the springs, 62, which on one side are connected to 25 a lever arm, 63, Fig. 5 of each of the toothed segments, 28, 28a, and 28b, and on the other side to the lugs, 64, of the driving sectors, 29, normally the toothed segments, 28, 28a, and 28b, are held 30 with their projections, 60, in contact with the lugs, 35 59, of the driving sectors, provided that the driving sectors 29 are rotated in the opposite direction of the arrow g. If, however, the driving sectors 29 are in their rest position as represented in Fig. 5, the tooth segments 28, 28a and 28b are 40 held against the action of their springs 62 by means of their tens transfer levers 88, 67, 68.

Tens transfer

On the shafts, 65 and 66, fixed in the machine 45 frame, small two-armed levers, 67 and 68, constructed as in Fig. 5, are swingably mounted. On each of the limbs, 67a and 68a, two noses, 69 and 70, are provided, which co-act with the "tens" cams, 75, on the toothed wheels, 71 and 50 72, of the one totalizer and with the "tens" cams, 75, on the toothed wheels, 73 and 74, of the other totalizer.

Further, on the shafts, 76 and 77, fixed in the 55 machine frame, pawls, 78 and 79, formed as in Fig. 5, are swingably mounted, which can co-act with the small levers, 67 and 68. By means of the springs, 83 and 84, which on the one side are connected to the noses, 80, of the small levers, 67 and 68, and on the other side to the 60 noses, 81, of the pawls, 78 and 79, the pawls, 78 and 79, are held with the levers, 67 and 68, in the normal position as represented in Fig. 5.

The pawls, 86, which are swingably mounted 65 on the shaft, 85, and co-act with the angle levers, 88, swingably mounted on the shaft, 87, are held in their rest position as represented in Fig. 5, by the springs, 89. The upwardly directed limb, 88a, of the two-armed lever, 88, co-acts with a lever, not shown, which is swingably mounted in 70 the column counter, V, which lever in the patent application Serial No. 555,331 is indicated by 80, and is exhaustively described, and which can co-act with the "tens" shift cam indicated there by, 87.

It may be remarked that the lever, 67 or 68, belonging to number wheels, 93, disposed farthest to the right of the cross totalizer, Q, and, 99, of the cross totalizer, Q1, are bent so far to the left that the same are able to co-act with the pawls, 78 or 79, following on the left, and so forth which on the following grounds must be the case. If for example the value 8 is registered in the number wheel, 93, farthest to the right of the cross totalizer, Q, and if the value 4 is to be added, in order to obtain a correct result, a 'tens' transfer must take place, which is effected as follows: In the instant in which the number wheel, 93, farthest to the right rotates from 9 to 0, the cam 75, of the toothed wheel, 71, of the cross totalizer, Q, acts on the nose, 69, of the lever, 67, and swings it against the action of the spring, 83, round its axis, 65, in the clockwise direction, out of the position represented in Fig. 5, whereby the pawl, 78, following on the left which lies in one plane with the second number wheel, 93, from the right, is swung under the pull of the spring, 83, so that the nose, 78n, of the pawl, 78, springs into the step, 67r, of the lever, 67, and holds this in position, so that in the swinging of the corresponding toothed segment, 28a, this does not push with its part, 28x, against the nose, 83p, and in this manner a further swinging movement of the toothed segment 28a of one unit in anti-clockwise direction will be released. In the swinging of the driving sectors, 29, and of the toothed segments, 28a, the toothed segment which cannot be held by the pawl, 78, further rotates the toothed wheel, 71, of the second place from the right of the cross totalizer, Q, through one division, so that the number wheel, 93, is rotated from 0 to 1, and a "tens" transfer has thus taken place. On the termination of this process, the roller 131 drops into the lower part 131A' of the cam 131A under the action of the spring 140, acting on the arm 132a, whereby the arms 132b, 132c, 132d are swung in the anti-clockwise direction around the shaft 51. With this, the part, 135, of the arm, 132c, of the lever, 132, acts on the nose, 136, of the pawl, 78, and swings this in the clockwise direction, whereby the nose, 78n, moves out of the step, 67r, of the lever, 67, so that the lever, 67, under the pull of the spring, 83, can again return into its rest position represented in Fig. 5. However, the lever 67 does not immediately return to its rest position, but rests with its nose 83p on the nose 28x of the segment 28a. After the releasing movement of the lever 67 by the pawl 78 has taken place, the raised part 130h of the cam 131A acts on the roller 131, whereby the arms 132b, 132c and 132d are rotated in clockwise direction. During this rotation the segment 28a is returned to its rest position, in which the nose 83p of the lever 67 falls behind the nose 28x of segment 28a, holding it thus in its normal position, as illustrated in Fig. 5.

Totalizer operation

The teeth 92 of the toothed segments 28 engage the toothed wheels designated at 91h in the accompanying drawings as well as in the former U. S. application Sr. No. 555,331, whereby in the swinging of the toothed segments 28 the value is registered in the column counters V in the additive or subtractive sense.

The toothed segments 28a may engage with the toothed wheels 71 or 72 according to whether the cross totalizer Q is set for addition or for sub-

traction. If the toothed wheels, 71, are in engagement with the teeth of the toothed segments, 28a, in the operation of the machine, the toothed wheels, 71, are acted upon by the toothed segments, 28a, in the direction of the arrow, a, 5 and the number wheels, 93, rotated in the positive sense through the toothed wheels, 72 and 94, and 94a. If, on the contrary, the toothed wheels, 72, are in engagement with the teeth of the toothed segments, 28a, the number wheels, 93, are 10 acted upon through the toothed wheels, 94 and 94a, in the negative sense, therefore opposite to the direction of the arrow, b, indicated in Fig. 5.

Totalizer shifting

15

To the left of the cross totalizer, Q, which is slidably arranged on the shaft, 96, fixed in the right-hand side wall, 95, of the machine frame, (Fig. 1) a sleeve, 96b, provided with a ring groove, 96a, is arranged, into which ring groove, 96a, projects the fork shaped end of a slide, 97, displaceably arranged on the front wall of the machine. The slide, 97, is provided with a knob, 98, by means of which the displacement of the cross totalizer, Q, to the right or to the left, on the shaft, 96, can be effected.

If the cross totalizer, Q1, is to operate in the positive sense the rotational direction corresponding to which is indicated by the arrow, the toothed wheels, 73, will engage with the teeth of the toothed segments, 28b, and if the cross totalizer, Q1, is to operate in the negative sense the toothed wheels, 74, will engage with the toothed segments, 28b.

In order to effect a displacement of the totalizer, Q1, to the right, a sleeve, not shown, having a ring groove, is provided on the left of the left-hand side wall, 100, (Fig. 3) of the totalizer, Q1, which sleeve likewise is displaceable with the cross totalizer, Q1, on the shaft, 101. With the ring groove of the sleeve, the fork-shaped end of a slide, 102, engages which is displaceable in the front wall of the machine and its end which projects from the front wall of the machine is provided with a knob, 103, by means of which a displacement by hand of the cross totalizer, Q1, is rendered possible to the right or to the left. The cross totalizers, Q and Q1, which are mounted on bearings on the adding machine, are displaceably arranged in order to enable multiplication to be performed by them in a simple manner.

Cam arrangement for totalizer engagement control

35

For controlling the engagement of the totalizers Q and Q1 with their actuating racks, the following arrangement is provided. On the shaft 57 two sleeves 128 and 57a are slidably but non-rotatably mounted. On each of the sleeves 128 and 57a there are fixed three cams. The cams 111 to 113 are provided for the totalizer Q1 and the cams 111a to 113a for the totalizer Q. The cams 111 and 111a are of such configuration that during one revolution of the same, the corresponding totalizer is kept in engagement with its racks 28b and 28a during the forward and the return movement of the racks (subtotal taking). The cams 112 and 112a are of such configuration that the totalizers are engaged with their racks prior to the forward movement of the racks and disengaged from the same prior to their return movement (total taking). The cams 113 and 113a are of such configuration that the totalizers are engaged with their racks only prior to the 75

return movement of the same (neutral or addition and subtraction position).

For displacing the cam series 111 to 113, with relation to the totalizer engagement control lever 114x, the sleeve 128 is provided with a knob 130. Furthermore, a pointer 129 is rotatable on the sleeve 128 but so mounted as to be axially displaceable therewith. The pointer 129 is held against rotation by its embracing the part 129a displaying the different positions D (neutral) T (Total) ST (subtotal) of the cam series in which positions the sleeve 128 may be held by any suitable means.

The cam series 111a to 113a is displaced by the following means. The sleeve 57a having a ring groove 57b engaged by pins 57c fixed on a vertical arm of an angle lever 57d slidably mounted on the frame. The end of the horizontal arm of the angle lever 57d projecting from the left hand side wall of the machine is provided with a handle 57e and a pointer 57f coacting with the marks D, F, St (Fig. 1) for the pointer 129. Similar means as for the sleeve 128 are provided for the angle lever 57d for holding it in the different positions of adjustment.

Totalizer engagement control

The setting of the totalizers, Q and Q1, for addition or for subtraction is obtained in the following manner: First the control of the cross totalizer, Q, for addition will be described. In this case, the pointer 57f has to be set to "d". Furthermore the lever, 104, by means of the knob, 104a, (Figs. 1 and 3) is moved from the neutral, (D), to addition, (A), whereby the same is acted upon in the clockwise direction, round its axis 105, and the connecting rod, 106, jointed to its rearwardly directed free limb, 105a, is moved in the direction of the arrow, c. The rod 106 then 40 swings the lever, 107, around its axis, 108, in the anti-clockwise direction, whereby the pin, 109, provided on the side wall, 95x, of the totalizer, Q is embraced by the recess, 110, of the lever, 107. The swinging of the lever 107 about the axis 108 45 is possible because the guide slot of the angle shaped guiding bracket shown above the connecting point of 106 and 107, is wide enough in order to permit such swinging movement of the lever 107. If now the hand crank or the motor key, 22, is operated, the driving shaft, 57, is rotated in the direction of the arrow, d, so that the cam 113a can act on the angle lever 114 thereby controlling the totalizer Q for addition, that is to say the totalizer Q is rocked round the shaft 96 in the anti-clockwise direction, whereby the toothed wheels 71 engage with the toothed segments 28a on their return movement.

If on the contrary, a value is to be registered in the totalizer, Q, in the negative sense, it is 50 only necessary to set the lever, 104, at subtraction, whereby the lever, 104, is swung in the anti-clockwise direction and the connecting rod 106, correspondingly moved in the opposite direction to that of the arrow c. The lever, 107, is thereby 55 acted upon in the clockwise direction around the point, 108, whereby the pin, 115, provided on the side wall, 95, of the totalizer, Q, is embraced by the recess, 116, of the lever, 107. If now the lever, 107, in consequence of the rotation of the 60 shaft 57 by the cam 113a through the lever 114 is acted upon in the direction of the arrow e the toothed wheels 72 of the totalizer Q engage the toothed segments 28a on their return movement, rotating thereby the number wheels 93 in the 65 negative sense.

If the lever, 104, is at neutral, D, the parts, 104, 106, and 107, assume the position represented in Fig. 3, whereby on the operation of the hand crank or of the motor key, 22, the lever, 107, through the parts, 57 and 113a, as well as through the lever, 114, is operated in the direction of the arrow e, but slides however, inoperative past the pins, 109, and 115, of the totalizer, Q, so that this is not displaced and no amount can be introduced into the same. By means of a locking pawl, 94A, 10 (Figs. 6 and 7) which is rotatably mounted at the points, 94B, on the two side walls of the totalizer, Q, (in Fig. 6 only the left-hand axis is visible) in the rest position (represented in full lines in Figs. 6 and 7) the toothed wheels are 15 arranged in totalizer, Q, as well as the number wheels, 93, are locked, i. e. an unintentional rotation is thus avoided. In the swinging into the addition position (represented in Fig. 6 in dotted lines) the projection, 94D, of the locking pawl, 94A, pushes against a pin, 94C, fixed in the machine frame, whereby the locking pawl, 94A, moves out of engagement with the teeth of the toothed wheels, 71, whilst the toothed wheels, 71, simultaneously engage with the teeth of the 20 toothed segments, 28a. The process in the swinging of the totalizer, Q, into the subtraction position is similar. In this, however, the swinging of the locking pawl, 94A, is effected through striking of the projection, 94D', of the locking pawl 30 94A, against the pin, 94H, (Fig. 7) fixed in the machine frame.

The swinging of the totalizer, Q1, for the purpose of introducing a value in the positive or negative sense is effected by the knob, 119, of the 35 lever, 120. If the same is set at addition, A, therefore acted upon round its axis, 121, in the clockwise direction so the connecting rod, 123, jointed on one side to the lever, 120, and on the other side to the lever, 122, swings the lever, 122, in the anti-clockwise direction, whereby the recess, 124, of the lever, 122, embraces the pin, 125, which is provided on the left-hand side wall, 100, of the totalizer Q1. As in the case of addition and subtraction the cam 113 cooperates with the 40 lever 114x and if now the hand crank or the motor key 22 is operated, the lever 122 is moved in the direction of the arrow f whereby the totalizer, Q1, is swung round the shaft, 101, in the anti-clockwise direction and thus the toothed wheels, 50 13, of the totalizer, Q1, are brought into engagement with the teeth of the toothed segments, 28b, and in the swinging of the toothed segments 28b, the number wheels, 99, are actuated in the positive 55 sense. As the introduction of a value in the negative sense into the totalizer, Q1, is obvious from the above description, it will not be here gone into further. It may be still remarked that in order to be able to displace the totalizer, Q1, to the right, between the toothed wheels disposed on the left-hand side and the left-hand wall of the totalizer, distance pieces 95y (Fig. 14) are arranged. Besides the right-hand side wall, 95a, of the totalizer, Q, and the right-hand side wall, 100a, of the totalizer, Q1, as is evident from Figs. 6, 7 and 3, are formed so small that on a displacement of the totalizers, Q and Q1, to the left, both of the side walls, 95a, or 100a, can move past the toothed segments, 28a or 28b, unhindered. Further, the pins, 109, 115, of the totalizer, Q, and 60 70 the pins, 125 and 125a, of the totalizer, Q1, are formed of such a length that in the displacement of the totalizers, Q and Q1, the same always remain in the operative position in relation to the levers, 107 and 122. The setting of the totalizers, 75 75

Q and **QI**, on neutral, total and sub-total is obtained as follows:—

On this sleeve 3 cams, 111, 112, and 113, are fixed. Furthermore, a pointer 129 is rotatably mounted on the sleeve 128 but so as to be axially displaceable therewith. If the pointer, 129, which is held against rotation by its embracing the part 129a as shown, points at neutral, D, in which position the lever, 114x, is disposed over the cam, 113, the cam, 113, acts on the lever, 114x, in the second half of the revolution of the shaft, 51, whereby the same acts upon the lever 122 in the direction of the arrow f. As a result the toothed wheels 73 or the toothed wheels 74 are brought into engagement with the toothed segments 28b at the beginning of their return movement in the direction of the arrow g according to whether the totalizer Q1 has been set by means of the knob 119 to addition or to subtraction. As soon as the wheels 73 or 74 have engaged the segments 28b, they transfer the amount into the totalizer Q1 additively or subtractively.

If by means of the knob 130, the pointer 129 is set for total T, the cam 112 is brought into the operative position in relation to the lever 114x. As a result, according to whether the knob 119 has been set to addition or to subtraction the wheels 73 or 74 are engaged with the toothed segments 28b immediately on the operation of the hand crank or motor key 22, that is to say, prior to the excursion of the segments 28b in the opposite direction of the arrow g. Consequently, the amount displayed by the number wheels 99, is withdrawn and the number wheels remain at zero, because the shape of the cam 112 is such that the wheels 73 or 74 are disengaged with the segments 28b as soon as they have completed their excursion in the opposite direction of the arrow g whereupon they return idly to their rest position.

If now the pointer 129 by means of the knob 130 is set for subtotal ST, the cam 11 comes into the working position in relation to the lever 114x. As a result, according to whether the knob 119 has been set to addition or to subtraction, the 45 wheels 13 or 14 are engaged with the toothed segments 28b also immediately on the operation of the hand crank or motor key 22, just as is the case in total taking. However, the shape of the 50 cam 111 is such that the wheels 13 or 14 remain in engagement with the segment 28b both in their excursion in the opposite direction and in the direction of the arrow g. Consequently, the amount displayed by the number wheels 99 is left 55 on the same as is usual in subtotal taking.

For controlling the totalizer Q of the neutral position for the total and sub-total positions on the shaft 51, three cams 111a, 112a and 113a similar to the cams 111, 112 and 113 are arranged so as to be slideable but incapable of rotation thereon. Said cams act on the lever 114 connected with the control lever 107 for the totalizer Q.

One of the three cams connected to one another is provided with a sleeve 51a having a ring cross 57b engaged by bolts 57c fixed on a vertical arm of an angle lever 57d slidably mounted on the frame. The end of the horizontal arm of the angle lever 57d projecting from the left-hand side wall of the machine is provided with a handle 57e and a pointer 57f coating with the marks D, T, St (Fig. 10), for the pointer 129.

Impression mechanism

In both the printing mechanism frame walls, 75 34, a shaft, 144, (Fig. 4) is fixed so as to be in-

capable of rotation. On this shaft, 144, angle levers, 145, alternately with a distance ring, not shown, are rotatably mounted. In the machine being described by way of example, ten angle levers, 145, are arranged.

On the downwardly projecting limb, 146, (Fig. 12) of each of the angle levers, 145, on each side of the same, a further lever, 147, is jointed. Of the levers, 147, only the left-hand one is visible in Fig. 4. The levers, 147, are rigidly connected to one another by means of pins, 148 and 149, which project through elongated holes, 150, 151, in vertically slidable arranged slides, 152. On the left hand levers, 147, noses, 153, are formed, which are so bent that they lie in the plane of the slides, 152. To the noses, 153, springs, 154, are connected, which at their other end are attached to noses, 155, of the slides, 152. The springs, 154, act upon the levers, 147, and the slides, 152, in such relation to one another, that the faces, 156, and 157, of the elongated holes, 150 and 151, of the slides, 152, rest against the pins, 148 and 149, fastened to the levers, 147, whereby the normal position of the slides, 152, in relation to the levers, 147, is determined. Springs, 158, which are connected on the one side to the noses, 159, of the slides, 152, and on the other side to an angle shaped part, 160, act upon the slides, 152, together with the levers, 147, in anti-clockwise direction, and in the direction of the arrow "D". The angle-shaped part, 160, is fixed by means of screws, 162, which pass through the rectangular downwardly bent lugs, 161, (in Fig. 4 only the right hand lug is visible) formed on its free ends to the two parts of the printing mechanism frame walls, 34. Through the upwardly-acting direction of pull of the springs, 158, the angle levers, 145, are rotated in a clockwise direction round a shaft, 144, and by the contact of their noses, 163, with the bar, 164, are held in their normal position. The horizontal pull of the springs, 158, acting on the parts, 152 and 147, is later described.

Furthermore, a connecting link 165 (Fig. 4), is jointed on each side of the lever 145, between which links at their other free ends levers, 166, are jointed. These are swingably mounted on a shaft, 167, which is mounted in the two side walls, 34, so as to be incapable of rotation, and are guided in slots, not shown; in an angle-shaped comb, 168, which is fixed to the side walls, 34, by means of the screws, 170, passing through the lugs, 169, which are downwardly bent at right angles. In Fig. 4 only the right hand fixing is visible. The free upwardly directed ends of the lever, 166, formed to correspond in Fig. 4 act in a manner to be described later on the already mentioned number types, 44. The downwardly directed free ends, 152a, of the slides, 152, (Fig. 4) are guided in slots of the comb, 171, according to Fig. 4, not shown, which at its right-angled upwardly bent lugs, 172, (in Fig. 4 only the right is visible) is fastened by means of the screws, 38, to both of the printing mechanism frame walls 65 whereby yielding of the slides, 152, laterally is avoided.

The slides, 152, are further provided with recesses, 114, (Fig. 4) through which a rod, 175, projects, which rod is fixed by means of screws 70 to an angle lever, 177, swingably mounted on the right-hand printing mechanism frame wall, 34, by means of a screw, 176, and also to an angle lever, 177, swingably mounted by means of a screw, not shown, on the left-hand printing 75

mechanism frame wall, 34, (the left hand angle lever, 177, is not visible in Fig. 4). Angle levers, 177, form with the rod, 175, the yoke, 177, 175 and 177. The limbs, 178, which are constructed as shown in Fig. 4, are at their free ends bent at right angles and co-act with the cams, 179, (in Fig. 4 only the right-hand cam is visible) on the shaft, 57.

The downwardly directed ends, 152a, (Fig. 4), 10 of the slides, 152, are of hook-shape. With the recesses, 180, of the same, a bridge, 181, of a U-shaped yoke, 182, 181, 182, can engage. The latter is swingably mounted by means of its limbs, 182, (of which in Fig. 4 only the right-hand limb 15 is represented) on the shaft, 183, which is mounted so as to be non-rotatable in the supporting frame walls, 34, of the machine. To the downwardly directed limbs, 184, of the yoke, 182, 181, 182, two parts, 185, are fixed one to each side of 20 each limb.

Between the parts, 185, a roller, 186, is rotatably mounted, which co-acts with the cams, 187, on the driving shaft, 57. To the limbs, 184, of the yoke, 182, 181, 182, springs, 188, are connected, which with one of their ends are attached to the upwardly projecting limbs of the angle levers, 177, of the yoke, 177, 175, and 177, whereby these and the yoke, 182, 181, 182, are acted upon in the clockwise direction. Consequently as already mentioned, the right-angled bent lower ends of the limbs, 178, of the yoke, 177, 175, 177, rest against the cams, 179, and the rollers, 186, arranged in the parts, 185, rest against the cams, 181, whereby the normal position of the yoke, 177, 175, and 177, as well as of the yoke, 182, 181, and 182, is determined. To the downwardly directed hook-shaped parts, 152a, of the slides, 152, noses, 190, (Fig. 4) are pressed out, which co-act with stops, 191, on the 40 two-armed levers, 192. The levers, 192, are swingably mounted on the shaft, 193, which is mounted so as to be non-rotatable in the two supporting frame walls, 34, of the machine. On the limbs, 194, of the two-armed levers, 192, noses, 45 195, are formed, which can co-act with the lugs, 196, formed on the driving segments, 29.

Automatic zero printing

In order to print the zeros to the right of a 50 number, the following arrangement is provided.

On the levers, 192, are lugs, 197, (Fig. 4) which are bent to the left, so that the lug, 197, on the lever, 192, disposed furthest to the right, rests on the face, 198, of the lever, 192, next to the left, 55 the lug, 197, of this lever again rests on the lever, 192, lying next to it on the left and so forth.

Springs, 199, (Fig. 4), which on one side are attached to the limbs, 194, of the levers, 192, and on the other side to pins, 200, fixed in the 60 machine frame, act upon the levers, 192, in the anti-clockwise direction. Through the contact of the noses, 190, of the slides, 152, against the stop faces, 191, of the levers, 192, by the horizontal pull of the already mentioned springs, 158, 65 the normal position of the slides, 152 is determined.

The arms, 201, of the driving sectors, 29, are of fork-shape at their lower ends, and embrace the pins, 30, provided on the feeler rods, 23, which 70 are arranged to co-act in a known manner, with the stops, 17, in the stop carriage, 15, representing the values, 0 to 9, or with the zero flap, 202.

The zero flap, 202, is swingably mounted on a suitable shaft, 203, which is mounted in any 75 suitable manner on the stop carriage, 15.

The stop carriage 15 and the zero flap are more clearly illustrated and described in British Patent 379,811.

The forwardly directed free ends of the horizontal limbs, 204, of the zero flap, 202, are bent 5 rectangularly upward, and its bent part projects upwards through an elongated slot, not shown, in the upper cover plate, 205, of the stop carriage, 15, and is held in its rest position represented in Fig. 3, by means of the spring, 206. 10

The platen, 33, is mounted in bearings in the carriage frame, 207, of the typewriter machine, 2, which frame is mounted on the rear carriage rail, 208, and on the front carriage rail, 209, in a known manner, and is held against a carriage 15 draw spring, not shown, acting in a direction of the arrow, A, by means of the known escapement mechanism, 210, of the typewriter machine in the required position.

Operation of the printing and impression mechanism

In the rest position of the printing bars 24, the zero types 44 are neither in front of the platen 33 nor in front of the impression levers 25 166 (Figs. 3 and 4). If therefore nothing is set in the stop carriage 15 and the rollers 56, on operation of the machine slide down to the lower part of the cams 58, the rail 53 releases the sectors 29. As a result they are rotated clockwise 30 by the springs 25 of the type bars, through the intermediary of the sector arms 50. Thus the sectors 29 may rotate until the noses 32 of the feelers 23 impinge against the upwardly projecting limb of the zero flap 202. From an inspection of Fig. 4, it will be evident that during this short rocking movement of the sectors 29, their lugs 196 are not able to act on the noses 195 of the levers 192. Consequently, no actuation 35 of the impression mechanism may take place. 40 If, however, in the two left hand stop rows of the stop carriage stops have been set which correspond to higher values than zero, the stop carriage 15 has moved two steps to the left (as viewed in Fig. 21). Accordingly, the two right 45 hand feelers 23 are free for movement, since the zero flap 202 which together with the stop carriage moved also two steps to the left is no longer in their path of movement.

If now the machine is operated, the two right 50 hand sectors 29 are rocked through a greater angle than the remaining sectors. Hence, the lugs 196 of the two right hand sectors 29 rock the appertaining levers 192 in the clockwise direction, thereby releasing the lugs 190 of the 55 two right hand slides 152 which by means of their springs 158 are rocked in the anti-clockwise direction until arrested by the rod 175 of the yoke 177, 175, 177. Thus, the recesses 180 of the two right hand slides 152 lie just beneath the bridge 181 of the U-shaped yoke 182, 181, 182. As soon as the latter is rocked in the anti-clockwise direction by means of the cams 187, the two right hand slides 152 are drawn downwards 60 through the intermediary of the bridge 181 of the yoke 182, 181, 182. As a result, the toggle joint 145, 165 is stretched, according to which the appertaining layers 166 are urged against the types 44 which through the intermediary 65 of the sectors 29 and the type bars 24 have been brought in front of the upper ends of the levers 166. Provided that a plurality of paper sheets are between the platen 33 and the types 44 owing to which the levers 147 are stopped somewhat 70 75

earlier in their downward movement, the slides 152 move in relation to the levers 147 thereby stretching the springs 154.

- After the cams 187 have released the yoke 182, 5 181, 182, the same is rocked anti-clockwise by means of the springs 188, releasing the slides 152 which through the intermediary of the springs 158 are drawn upwards. Thus, the levers 145, 165 and 166 are restored to their rest position. 10 Shortly prior to the completion of the revolution of the shaft 57, the cams 179 act on the yoke 177, 175, 177. Consequently, the latter is rocked anti-clockwise, whereby the rod 175 of the same swings the two right hand slides 152 anti-clockwise so that the levers 192, after the return of the sectors 29 to their rest position, may fall in front of the lugs 190 of the slides 152, thus locking the slides in their rest position. The sectors 29 are returned to their rest position by 15 the cams 58 through the intermediary of the yoke 54, 53, 54.

On a rail, 211, fixed to the paper carriage of the typewriting machine, any desired number of column counters, V, are mounted so as to be 25 readily attached and detached, in order that their position longitudinally of the rail, 211, may be arranged to correspond to the column work to be performed.

The column counters, V, attached to the carrying rail, 211, correspond to those described in 30 patent application Serial No. 555,331, and may be set to each type of calculation.

It may be here remarked that the column counters or totalizers, V, and the totalizers, Q and Q1, 35 mounted on the adding machine are so arranged in relation to one another that they can be operated together by one and the same driving sectors, 29, whereby the whole arrangement is constructed in an extremely simple manner and 40 the totalizers and typing text on the platen, 33, may be readily inspected.

If, for example, the amount of 32535, registered in the totalizer Q is to be transferred hundred-fold to the totalizer Q1, first of all, the totalizer Q1, which at that time is in its zero condition, 45 is displaced through two places to the right (as illustrated in Fig. 3a). Thereupon, knob 104a for the totalizer Q, is set to addition, that is on mark A (Fig. 1). The knob 57e (Fig. 11) is 50 now displaced in the direction of the arrow A until the pointer 57f points to the mark T (total) whereby the total is brought opposite the lever 114, connected to rod 107 (Fig. 3). Furthermore, the knob 119 for totalizer Q1 is also set to addition, 55 that is to mark A (Fig. 1) and the knob 130 (Fig. 11) is pulled out in the opposite direction to arrow A until the pointer 129 points to mark D (Fig. 10) whereby the cam 113 (Fig. 11) is opposite the lever 114x, connected to rod 122 (Fig. 3).

If now the machine is operated, cam 112a rocks the lever 114 clockwise, whereby the rod 107 is displaced in the direction of the arrow e. Since the knob 104a has been set to addition, 60 the recess 110 of rod 107 has engaged the pin 109 of the totalizer Q. As a result, the totalizer Q, by the displacement of the rod 107 in the direction of the arrow e will be rocked anti-clockwise so that the wheels 71 come into engagement with 65 the segments 28a. If now, while the machine is operated, the sectors 29 are rocked clockwise, the segments 28a turn the wheels 71 and, through the intermediary of the wheels 72 and 94, the 70 numeral wheels back to zero which zero position 75 is brought about by the abutment of the noses 75

of the wheels 71 against the noses 69 of the tens transfer levers 67 which for this purpose have been locked in their rest position by any suitable locking rod (not shown), preventing the levers 67 from rocking in the clockwise direction. 5

Accordingly, the segments 28b, by means of the sectors 29 are rocked through the same amounts as the segments 28a. Now, by means of the cam 113, the lever 114x is rocked clockwise, whereby the rod 122 is displaced in the direction 10 of the arrow f. As a result, the totalizer Q1, through the engagement of the recess 124 of the rod 122 with the pin 125, is rocked anti-clockwise, so that the wheels 73 of the totalizer Q1 will come into engagement with the segments 28b. 15 At the same time, the cam 112a has turned so far, that the lever 114, by means of a spring (not shown) is rocked anti-clockwise, whereby the totalizer Q, through the intermediary of rod 107 is rocked out of engagement with the segments 28a. 20

If now, the sectors 29 are rocked anti-clockwise to their initial position, the amount of 32535 will be added into the third to the seventh decimal place from the right of totalizer Q1. Therefore, the totalizer Q1 shows now the amount 3253500 25 on account of the fact that the units and the tenths place of the same have not been affected.

Now, it may be assumed that the totalizer Q1 is held in its displaced position by two decimal places to the right and that in the units and 30 tenths position, there are figures other than zero.

If now, a total is taken from the totalizer Q1 and transferred to the totalizer Q it is obvious that the figures of the units and tenths places of the totalizer Q1 are not transferred, since no 35 segments 28b are opposite these decimal places. Accordingly superfluous places are cancelled while transferring from one totalizer to another although the cancelled figures remain stored in the totalizer from which the total is taken. 40

By forming the totalizer Q as double totalizer Q, Q', it is possible to store amounts for later application. For this purpose, the double totalizer Q, Q' is displaced so far to the right that the units place of the totalizer Q' is opposite the right hand sector 29. Any amount may then be transferred from the totalizer Q1 to the totalizer Q'. If then the double totalizer is brought back to the position illustrated in Fig. 3a, the amount in the totalizer Q' remains un- 50 affected. 55

In a similar manner the totalizer Q1 or both of the totalizers Q and Q1 may be constructed as double totalizers.

I claim:—

1. In a machine of the class described, a totalizer including two sets of gears for operating said totalizer for addition and subtraction, respectively, means for operating the totalizer including a series of toothed actuators, and a drive shaft, said totalizer being mounted to swing in opposite directions respectively, to effect engagement of one or the other of said sets of gears with said actuators, and add-subtract control mechanism comprising a lever adapted to swing said totalizer in either direction and settable to predetermine the direction in which said totalizer shall be swung, a cam on said drive shaft, an operating connection between said cam and lever, and manually manipulative means for setting 60 said lever. 65

2. In a machine of the class described, a totalizer including toothed number wheels, means for operating said totalizer including a series of toothed actuators, and a drive shaft, said total- 70 75

izer being mounted for swinging movement to effect engagement and disengagement of said wheels and actuators, means for swinging said totalizer including a lever suitable to predetermine whether or not said totalizer shall be swung, a key for setting said lever, and lever operating

means including a series of cams on said shaft for operating said lever for addition, and total and subtotal taking operations, respectively, said cams being shiftable to predetermine the character of operation to be performed.

HUGO KÄMMEL.
